UNITED STATES PATENT OFFICE.

WILLIAM MAIN, OF BROOKLYN, NEW YORK.

ELECTRIC INDUCTIVE TRANSLATOR.

SPECIFICATION forming part of Letters Patent No. 361,770, dated April 26, 1887.

Application filed September 8, 1886. Serial No. 212,976. (No model.)

To all whom it may concern:

Be it known that I, WILLIAM MAIN, a citizen of the United States, residing in Brooklyn, in the county of Kings and State of New York, have invented certain new and useful Improvements in Electric Inductive Translators, of which the following is a specification.

This invention relates to apparatus for translating high-tension currents on one circuit into low-tension currents on another, or vice versa.

In the distribution of electric energy from a central source to a distant point where the current is consumed it is desirable to employ currents of high tension, in order that the loss of energy in transmission may be reduced to the minimum, and in order that the line-conductors may be of small size and consequently inexpensive. The transmission of such currents is thus conducive to economy both in the first cost and in the subsequent operation of the installation; but for those purposes wherein the consumed currents may be of considerable volume and low tension, notably in incandescence electric lighting, the transmission of high-tension currents over the line is inadmissible unless some means be provided for converting them into low-tension currents before they reach the consuming devices. It is also frequently desirable to feed various current-consuming devices with electric currents of different character, some of high tension and low volume, others of low tension and high volume, but all derived from the same source. These facts have led to the invention of various systems of electric distribution in which the character of the current is changed by special devices before it is finally utilized. The following are the most important methods suggested for this purpose:

40. *First, distribution through secondary batteries.*—The line or high-tension circuit is used to charge the accumulators, and when charged they are disconnected therefrom and connected to local circuits, being at the same time coupled in different order, whereby they supply to their local circuit currents of low tension and considerable volume, suitable for incandescence lighting.

45. *Second, distribution of alternating currents through induction-coils.*—The line is fed with high-tension alternating currents, which trav-

erse in series the fine-wire primaries of induction-coils. The local circuits are connected in multiple to the coarse-wire secondaries of these coils, whereby alternating currents of 55 high volume and low tension are induced in the local circuits.

50. *Third, conversion of continuous high-tension into alternating low-tension currents.*—The line is fed with high-tension currents, which are distributed by a commutator into the high-resistance primaries of a series of induction-coils entering them successively, and being alternately reversed in each coil. The low-resistance secondaries of the respective coils each feed a separate local circuit with alternating currents of 65 low potential.

60. *Fourth, conversion of continuous line currents into continuous induced currents of different character through "inductive translators."*—The translator consists of a series of induction-coils with primary and secondary commutators. The line is fed with (for example) high-tension currents, which are distributed through the primary commutator to the primaries of the 70 induction-coils, which they enter successively, being alternately reversed in each coil. The alternating currents thereby induced in the secondary coils are collected and rectified by the secondary commutator and discharged to 75 the local circuit as continuous currents of (for example) low tension and considerable volume. The translator thus constructed may be proportioned to convert any character of current into a current of any other character. 80

85. The fourth of these systems affords the best promise of practical success, and it is mainly to this that my present invention relates, although it is in part applicable to the third system.

90. The inductive translator heretofore designed, on which my invention is most immediately an improvement, may be described as follows: The series of induction-coils consist of a Gramme ring wound with primary 95 and secondary coils, with their terminals carried to the segments of the respective commutators. The ring and commutator-segments are stationary and the brushes of the two commutators are both mounted on one shaft and revolved together, whereby their synchronous movement is assured, or the ring and seg-

ments may revolve and the brushes may be stationary. The arrangement is thus essentially that of a series of induction-coils with their primaries joined together and connected 5 between them to the segments of the primary commutator and their secondaries joined together and connected to the segments of the secondary commutator. The line-current thus flows through the primaries around opposite 10 halves of the circle or ring on opposite sides of what may be termed a "neutral line," which revolves with the commutator-brushes, and the currents induced in the secondary coils flow in opposite directions on opposite sides 15 of another neutral line revolving with the first, but at right angles thereto. Each primary coil receives the line-current in one direction until the neutral line in its revolution crosses it, whereupon the current is reversed 20 for a half-revolution. The resulting induced currents are crossed by the secondary neutral line at the instant of their reversal, and, as the secondary brushes at that instant reverse their relation to the external local circuit, they are 25 rectified and discharged to that circuit as continuous currents. Exterior to the Gramme ring is arranged a magnetic bridge or body, which affords an inductive magnetic connection between the opposite poles of the ring, 30 thereby intensifying the inductive action. This bridge rotates with the rotating poles of the ring and with the rotating brushes of the commutators. By setting it to follow the poles in their revolution it is made the means of 35 imparting rotary motion to the brushes, thus constituting an electromotor, rendering the translator self-propelling. My present invention constitutes an improvement upon this machine, designed to perfect it for practical 40 application.

The principal object of my invention is to provide means for regulating the machine and rendering it self-governing, in order that the character of current which it gives out may 45 be determined within reasonable limits by means of suitable adjustments, and that when once thus determined the resulting current shall be maintained practically uniform.

My invention also has for its object to render 50 the translator equally capable of receiving high-tension and giving out low-tension currents, or of receiving low-tension and delivering high-tension currents.

My invention also aims to perfect and develop 55 the mechanical construction of the translator in order to render it more efficient and economical.

The preferred construction of my improved translator consists of a double-wound Gramme 60 ring with its low-resistance coils joined to the segments of one commutator, and its high-resistance coils joined to the segments of another commutator. On a revolving shaft are the brushes of these commutators, one being 65 set a quarter-revolution ahead of the other, and a magnetic bridge or yoke is carried by this shaft, with its ends in close proximity to

the Gramme ring, thereby serving both as a magnetic connection between the opposite poles and also as a motor for driving the shaft. 75 A brake is applied to govern the speed of rotation of this shaft, and the pressure on this brake is regulated by the action of electromagnets in such manner that the speed of rotation is so proportioned as to attain a uniform potential or a uniform volume of current or other desired result, according to the adjustment. Switches are provided, by means of which various conditions may be effected for the control of the brake, in order to determine the character of current to be given out by the machine and adapt it for various uses. 80

I will now proceed to describe in detail the preferred form of my translator with reference to the accompanying drawings, wherein— 85

Figure 1 is a plan view of the apparatus on a reduced scale. Fig. 2 is a vertical mid-section on a larger scale, cut in the plane of the line 2 2 in Fig. 1, and partly in elevation. Fig. 3 is a plan view, partly in horizontal section, cut in the plane of the line 3 3 in Fig. 2. Fig. 4 is a similar plan in section on the line 4 4 in Fig. 2. Figs. 5 and 6 are plans of details of the electrical connections detached, and Fig. 7 is a diagram showing the electrical 90 circuits and connections. The remaining figures illustrate modifications. Fig. 8 is a diagram illustrating the winding of the induction-coil like a Siemens armature. Fig. 9 is a side elevation of a translator with such winding. Fig. 10 is a diagram illustrating the circuits and regulating-coils. Fig. 11 is a plan of a translator which is governed by automatically-shifting commutator-brushes instead of by a brake, and Fig. 12 is a vertical trans- 95 verse section thereof. 100

Referring to Figs. 1 to 4, let A designate the base of the apparatus, on which is mounted a fixed frame consisting of a horizontal plate, A', supported rigidly on four upright posts, 110 A" A". On the base is fixed the Gramme ring B and the two commutators C and D. In the center of the ring is stepped an upright shaft, E, the upper end of which is guided by a bearing in the plate A'. On this shaft are fixed 115 the brushes c c of the commutator C and the brushes d d of the commutator D. A revolving armature or magnetic yoke, F, is also mounted on this shaft, with its opposite ends or pole-pieces in close proximity to the Gramme 120 ring. These are the essential parts of the translator without its governing or adjusting devices. I will now proceed to describe in detail the parts thus far enumerated.

The Gramme ring B is preferably constructed with a core, b, of soft-iron wire, wound 125 into an annular coil. Around this coil are wound two series of coils, the high and low resistance induction-coils. The low-resistance coils C' C' consist of a few turns of coarse insulated wire wound directly upon the core. The high-resistance coils D' D' consist of many turns of comparatively fine insulated wire wound around the low-resistance coils. The 130

construction is clearly shown in Fig. 2. The several coils of each series have their terminals connected to one another serially and to the respective segments of the corresponding commutator, as is usual in the winding of Gramme-ring armatures. In the construction shown there are twenty-four coils to each series; but more or less may be made, as desired. The coils are wound with radial centers and parallel sides, leaving angular gaps between them on the outer side of the ring. These gaps are filled with angular core projections *a a*, each of which is slipped into the core *b* from the outside, having the shape shown at the right in Fig. 2. These core projections are built up of thin sheets of iron stamped out to the outline shown in Fig. 2, those at the outside being successively shorter, in order to give them a wedge shape (in plan) to fill the angular gaps between the coils. These projections *a a* constitute, substantially, a part of the core, the effect being analogous to that of a core having such projections formed upon it, as in the Brush armature.

25 The low-resistance coils *C' C'* are connected to the segments of the commutator *C*, and the high-resistance coils *D' D'* are connected to the segments of the commutator *D*. The method of making these connections is clearly shown 30 in Fig. 2.

The high-resistance commutator *D* is swept by brushes *d d*, which are carried by arms *e e*, fixed to the shaft *E*, but insulated therefrom and from each other. Their construction is shown in Fig. 5, the brushes being mounted in clamps pivoted on the rods and pressed against the commutator by the torsional tension of adjustable spiral springs *e' e'*. From the clamp of each brush *d* a wire, *d'*, leads and passes 40 into a vertical groove in the shaft *E*, (see Figs. 2, 3, and 5,) through which it ascends to one or other of two insulated grooved rings, *f f*, carried by the shaft near its upper end. In the grooves of these rings rest the ends of take-off clamps *I I*, Fig. 2, the construction of which is shown in Fig. 6. They are divided, the halves coming together to engage the grooved rings, and being then clamped in place by nuts on screws *I' I'*, which are fixed to, but 45 insulated from, the plate *A'*. From these screws *I' I'* wires (not shown) lead eventually to the two high-resistance binding-posts *H H*.

The low-resistance commutator *C* is swept by brushes *e e*, carried by arms *g g*, which are fixed to the shaft *E*, but insulated therefrom and from each other in like manner to the arms *e e*. The brushes are mounted in clamps in the same manner as the brushes *d d*. The electrical connection is from each brush through 55 its clamp and its arm *g* to a screw, *g'*, Fig. 4, by which the arm is fastened to the yoke *F*, Fig. 3. This yoke consists of a horizontal cross-plate, *l*, mounted diametrically on the shaft *E*, with vertical cores *m m* extending 60 downward from the ends of this plate and terminating in laterally-extended pole-pieces or plates *n n*, which curve as close to the

Gramme ring *B* as possible, but do not touch it. On the cores *m m* are wound coils *G G*, of coarse insulated wire, which terminates at screws *i i'*, which screws pass through the iron yoke-plate *l*. The screws *i i'*, near opposite ends of the yoke-plate, make contact with conducting-plates *h h*, which extend thence toward and beyond the middle, their ends being formed 75 with arc shaped slots *h' h'*, through which project the screws *g' g'*. The screws *i i'* and *g' g'* and the plates *h h* are all insulated from the yoke-plate *l*. The screws *g' g'* serve not only to make electrical connection between the commutator-brushes *c c* and the plates *h h*, but also to mechanically clamp together the brush-arms *g g* and the magnetic yoke *F*. By loosening these screws the arms and yoke can be adjusted to different relative angles, the screws *g' g'* moving in the arc-shaped slots *h' h'*. From the screws *i i'* the electric connection is continued through wires *j j'*, the former of which extends up through a groove in the shaft *E* to a grooved ring, *k*, and the latter of which communicates through a plate, *j''*, with a grooved ring, *k'*. In the grooves of these rings *k k'* rest the ends of take-off clamps *J J*, (duplicates of the clamps *I I*.) which lead to opposite fastening-screws, *J' J'*, Figs. 1 and 3. From 90 these screws the connections lead eventually to the low-resistance binding-posts *L L*, Fig. 1. All these circuit-connections may be readily traced in the diagram, Fig. 7. The high-resistance circuit extends from one post, *H+*, by wire 5, to take-off clamp *I*, and thence through grooved ring *f*, wire *d'*, brush *d*, commutator *D*, to outer coils, *D' D'*, of ring *B*, thence back by commutator *D*, the other brush *d*, wire *d'*, ring *f*, and clamp *I*, and by wire 6, 100 switch *M'*, wire 7, and wire 8 to the other post, *H*. The low-resistance circuit extends from one post, *L+*, by wire 9, to clamp *J*, thence by ring *k*, wire *j*, screw *i'*, through one coil *G* by screw *i*, plate *h*, screw *g'*, arm *g*, brush *e*, commutator *C* to the inner coils of ring *B*, thence 105 back by commutator *C*, the other brush *e*, arm *g*, screw *g'*, plate *h*, screw *i*, the other coil *G*, screw *i'*, wire *j'*, ring *k'*, clamp *J*, and by wire 110, switch *N'*, and wires 11 and 12 to the other post, *L-*.

It will be observed that the coils *G G* receive a continuous current in one direction, whereby the yoke *F* is magnetized, the plates *n n* constituting its opposite poles. The flow 120 of the primary current through the coils of the Gramme ring *B* develops diametrically opposite poles therein, as is well understood, and these poles revolve with the commutator-brushes. The yoke *F* is arranged with its *N* pole adjacent to the *S* pole in the ring, and with its *S* pole adjacent to the *N* pole in the ring, thereby forming a magnetic bridge extending diametrically from one pole of the ring to the other, the effect of which is to establish a closed magnetic circuit, and, consequently, to intensify the magnetic excitation 125 of the ring. This effect will result whether the yoke is an electro-magnet or a permanent 130

magnet or a simple bridge of soft iron; but I prefer to render it an electro-magnet by supplying the coils G G, as thereby the magnetization of the ring is increased by induction 5 from the yoke.

The yoke is utilized as an electro-motor for driving the commutator-brushes by setting it on the shaft E, with its pole-pieces slightly behind the poles in the ring, so that the latter, as they advance, will continually attract the yoke, causing it to revolve, and thereby revolving the shaft E with the brushes. The relative angles of the yoke and brushes may be adjusted (within reasonable limits) without disturbing the electrical connections by loosening the screws g' g' and turning the parts to the desired relative positions, which is permitted by the arc-shaped slots h' h', and then tightened the screws again.

20 While I prefer to drive the commutator-brushes by means of an electro-motor, I wish it understood that I am not limited thereto, as it is not essential that the machine be self-propelling. In situations where there is shafting 25 turning at uniform speed the motor may be omitted, and the shaft E may be belted or geared to the shafting or other source of power. In that case the yoke F will still be used either with or without the coils G G. In that case 30 also it may be necessary to provide some other means of regulating the machine than the one which I shall presently describe.

In constructing a practical electric translator it is highly important that it be made 35 capable of governing or regulating itself, in order not only to give uniform results when running with uniform conditions in both the primary and secondary circuits, but also to adapt itself to varying conditions of one or 40 both of these circuits, in order to compensate for such variations. It should be so constructed that the electrician in charge may adjust it to any given conditions of primary current and of consumption of energy in the secondary circuit, and having so adjusted it he 45 may leave it running with the knowledge that it will automatically provide (within reasonable limits) for the maintenance of the required conditions, notwithstanding considerable 50 change made from time to time in the demands upon the secondary or consumption circuit. It should also, when desired, be capable of compensating irregularities in the primary or supply circuit, although these are usually less 55 in degree than those arising in the secondary.

To this end my invention provides an electrically-controlled brake for governing the speed of revolution of the shaft E. This brake is applied through a lever, which carries the 60 armatures of two oppositely-acting electro-magnets or groups of electro-magnets, adjustable springs being provided to press against the lever. The action of the magnets is controlled by switches, by means of which either 65 group of magnets may be cut out limb by limb. Other adjustments are also provided.

Before describing the electrical arrange-

ments and operation I will describe the mechanical construction of this brake and its operating mechanism. Referring to Fig. 2, the shaft E is 70 stepped upon a coned pivot, p, fixed at the bottom of an oil well or cup, K, which holds a quantity of oil to lubricate the stepped bearing of the shaft. The upper end of the shaft is reduced at q, forming a journal which rotates in a sleeve, O, which sleeve is steadied by a tube, q', forming part of a cap, q'', which is fastened to the top plate, A'. The sleeve O is stationary, being pivoted by a universal joint to the middle of a lever, P. The bottom of this sleeve is formed 80 with a disk, O', which comes in contact with a disk, E', which is fixed on the shaft E, and turns therewith. An oil-cup, K', is fixed on the shaft, and incloses the disks E' O' and journal q, so that these parts run in oil, thereby 85 reducing friction to the minimum. The disk O' constitutes the friction-brake, being pressed downwardly against the disk E', with a pressure varying from time to time. This pressure is communicated to it through the lever P. 90 This lever extends horizontally over the machine, and is jointed at its opposite ends to rods o o, which extend thence downward, and bear the armatures of the respective regulating-magnets or groups of magnets T S. The 95 lever P has two fulcrum-bearings, f' and f'', and is itself formed with coinciding pivot-holes, through either of which a fulcrum-pin, p', may be passed. In this way the fulcrum may be shifted to either side of the center of the lever. 100 Adjustable retracting-springs u and u' are placed under the opposite arms of the lever.

With the fulcrum at the left, as shown in Fig. 2, the magnet S, when excited, acts to apply the brake, while the excitation of the magnet T tends to release the brake. If the fulcrum is shifted, the effect of the two magnets is reversed.

The magnets T S each consist of four cores 110 screwed into one base-plate, each core being wound with an independent coil.

The armatures t s of the respective magnets, T S, are magnetically connected with the base-plates thereof, through the medium of central cores, t' and s', respectively. These cores 115 have the armatures fastened to their upper ends, and are screwed upon the rods o o, being thus vertically adjustable upon the rods, in order to bring the armatures closer to or farther from the ends of the four fixed cores of the 120 magnets, and thereby increase or decrease the strength of the attraction. To permit of their vertical movement, they are passed freely through holes in the base-plates.

The magnet T is the direct magnet, its coils 125 being installed serially in the primary and secondary circuits, while the magnet S is the shunt-magnet, its coils being installed in derivation. I will now explain the electrical connections of these coils with reference to Fig. 7, 130 where the four coils of each magnet are shown as if arranged in a row side by side. The magnet T has two coarse-wire coils, a' a'', for the low-tension circuit, and two coils, b' b'', of finer wire,

for the high-tension circuit. The magnet S has four high-resistance fine-wire coils, $c' c^2 d' d^2$. The eight coils make their connections through four switches, M N M' N'. (Shown also in their 5 preferred form in Fig. 1.) The high-resistance switches M M' have their levers connected by wires 7 and 8 with the binding-post H—. The low-resistance switches N N' have their levers connected by wires 13 12 and 10 11 12 respectively, with the binding-post L—. Each switch has four contact buttons or plates, numbered 1, 2, 3, and 4, respectively. Nos. 1 and 2 connect with the like-numbered 15 coils; No. 3 connects with the main circuit, cutting out the coils, and No. 4 is a blind contact having no connection.

The coils of the shunt-magnet S are controlled by the shunt-switches N and M. Button No. 1 of the switch N connects by wires 20 14 15 with coil c' , whence wires 16 17 lead to main wire 9, and thence to the other binding-post. Button No. 2 connects by wire 18 with coil c^2 , whence wires 19 15 lead to coil c' , as before; hence if the lever of this switch be 25 turned to button No. 1 one coil, c' , will be in a shunt of the low-resistance circuit, and if it be turned to No. 2 two coils, c^2 and c' , will be included serially in a shunt of that circuit. The buttons 1 and 2 of switch M are connected in 30 precisely similar manner to the coils $d' d^2$. Thus it is clear that by a manipulation of the switches M N the action of the shunt-magnet S may be controlled at pleasure, either one or two or neither of its coils being excited by a 35 shunt from either the primary or secondary circuit.

The coils of the magnet T are controlled by the direct switches M' N', which have their buttons 1 and 2 connected with the coils $b' b^2$ 40 and $a' a^2$, respectively, in precisely similar manner to that already described with reference to switch N, except that they are connected in series instead of shunt. Thus, if switch M', for instance, be turned to button No. 1, the entire high-tension current passes through coil b' , and if it be turned to No. 2 the entire current passes through coils b^2 and b' in series.

Contacts No. 3 of the direct switches M' N' are used to cut out the coils of magnet T, causing 50 the current to flow from one binding-post, through the commutator and Gramme ring, to the other binding-post. The contacts No. 3 of the shunt-switches M N are used to short-circuit the commutator and ring, causing the 55 current to flow from one binding-post directly to the other, and thereby throwing the machine out of action.

I will now proceed to describe how the regulation of the machine for different conditions 60 is effected. The most important conditions are four in number, namely: A, translating high-tension currents into low-tension currents of uniform potential; B, translating high-tension currents into low-tension currents of uniform 65 form volume; C, translating low-tension currents into high-tension currents of uniform potential; and, D, translating low-tension cur-

rents into high-tension currents of uniform volume. I will state the principal adjustments for these four conditions.

A. *High into low tension, uniform potential.*—Probably the most frequent use to which my machine will be put is to operate incandescent lights in multiple arc from an arc circuit. The arc circuit then becomes the primary and 75 the incandescent circuit the secondary. The former has a uniform current of varying tension. The latter must have a uniform potential with a varying current, which should increase or diminish in proportion as more or 80 fewer lamps are lighted. In such case the arc circuit from which the machine is to be fed is connected to the binding-posts H H, and the incandescent or consumption circuit is connected to the posts L L. To adapt my machine for this service, the fulcrum-pin of the lever P is put through the left-hand hole f' , the left-hand spring u is slackened, and the right-hand spring u' is tightened until the pressure on the brake is relieved, so that the 85 machine will start freely when the current is turned on. The coils of the magnet T may be shunted out by turning the switches M' N' to the contacts 3 3. The switches M N may be turned to the contacts 1 1, thereby shunting one primary and one secondary coil of the magnet S into derivation with the primary and secondary circuits, respectively, or to contacts 2 2, thereby shunting two coils into each circuit, or otherwise, as may be required. 90 When the machine is started, its speed gradually increases until the difference of potentials at the binding-posts becomes sufficient to shunt a derived current through the coils $c' d'$ sufficient to so magnetize the magnet S as to attract its armature s , which pulls down the lever P, overcoming the tension of the spring u' , and applying the brake O', which checks the speed of rotation and reduces the secondary current to a given potential. The potential of the secondary current will depend upon, 95 first, the number of coils of the shunt-magnet S in circuit; second, the proximity of the armature s to its poles; third, the retractile force exerted against the magnet S; and, fourth, 100 the variations that may occur in the primary current. So long as the primary current remains uniform and the resistance in the secondary circuit is unchanged and the adjustments of the machine are not altered, the potential of the secondary current will remain constant. A given potential being desired, 105 the machine must be so adjusted as to supply that potential. If it be too low for the requirements, it may be raised by either one or 110 more of the following adjustments: First, by cutting out one or more coils of the magnet S from either the primary or secondary circuit; or, second, by moving the armature s farther from the poles of the magnet; or, third, by increasing the retractile force exerted against the magnet S, and, conversely, to lower the potential 115 the opposite of either of these adjustments may be made. To increase the retractile force,

it is necessary either (a) to slacken the spring u , or (b) to tighten the spring u' , or (c) to generate a counter-attraction by switching one or more of the coils of magnet T into circuit, or, 5 the latter being already in circuit, (d) to lower the armature t into closer proximity to the poles. The desired potential having been secured by adjustment, with a uniform resistance in the secondary circuit, it is necessary to adjust 10 just for the compensation for variations of resistance in that circuit. When more lamps are lighted in multiple, the resistance decreases and the potential falls; hence the magnet S relaxes and the brake-pressure is relieved, thereby 15 by permitting the shaft to revolve faster until the original potential is restored. If the brake-pressure is relieved in an insufficient ratio to effect this, or in a ratio so great as to more than compensate for it, the adjustments must be altered accordingly until a proper compensation is effected. It is unnecessary here to give minute directions for these adjustments, as any competent electrician will be able to meet all practical requirements of adjustment 20 after a little time given to experimental practice. Variations in the primary current may usually be ignored. The effect of a rise of potential in the primary is to increase the excitation of the coils $d' d^2$, and so apply the brake 25 harder, thereby neutralizing the effect of the increase by reducing the speed of rotation. The effect of an increase in volume is to more strongly excite the coils $b' b^2$, and consequently to relieve the brake and let the speed increase, 30 which apparently would aggravate the effect upon the secondary current; but in fact the magnet S will act so powerfully to apply the brake that it overcomes the opposing tension of the magnet T, thus in fact reducing the variations 35 of the attraction of the latter to simply an automatically varying retractile force.

B. High into low tension, uniform volume.—The machine might be used under these conditions for driving electro-motors of low resistance in series in a secondary circuit fed by an arc circuit. The arc circuit is connected to posts H H and the consumption circuit to posts L L, as before. The fulcrum of the lever P will be shifted to the right, spring u' will be slackened, spring u tightened, and the coils $a' a^2$ of magnet T used as the principal regulating-coils. The magnet S will be used as a retractile force, chiefly.

C. Low into high tension, uniform potential.—If a circuit feeding incandescent lamps in multiple were desired to feed high-resistance incandescent lamps or motors in multiple, or a single arc lamp, this condition might be desirable. The feeding or supply circuit will be connected to binding-posts L L and the high-tension consumption-circuit to posts H H. The fulcrum of lever P will be at the left, and the coils $d' d^2$ will be chiefly depended on for regulation.

D. Low into high tension, uniform volume.—This condition would occur if two or more arc lamps in series were desired to be fed from an

incandescent multiple circuit. In such a case it might prove more convenient or economical to install one of my translators in the circuit than to erect a high-tension dynamo and drive it from shafting or from a steam-engine. The machine will be fed through posts L L, and will give out its induced currents through posts H H, as in the last case. The fulcrum of lever P will be placed at the right, and the coils $b' b^2$ of magnet T will be chiefly depended on to effect the regulation. 70 The regulating device may be modified in various ways, as will be well understood by electricians. For instance, instead of two coils of each kind, as $a' a^2, b' b^2$, &c., there may be only one, or there may be three or more. The current through them may be increased or diminished by switches, or by the varying of shunted resistances, or in any other way known to electricians. Solenoids may be used in place of magnets. The grouping of the different kinds of regulating-coils may be varied in any way desired, to adapt the machine for any unusual 85 conditions. For instance, instead of having the shunt-coils at one end of the lever P and the direct circuit-coils at the other end, the primary circuit-coils may be arranged at one end and the secondary circuit at the other. 90 These alterations are simply matters of preference, or such changes as are within the scope of practical adaptation to suit different conditions, and do not affect the essentials of my invention, nor is my invention limited to a 95 Gramme ring.

In Figs. 8 and 9 I have shown a modification of my invention, wherein a Siemens drum armature is used in place of a Gramme ring. The drum B is wound with coils of primary 105 and secondary wire, each arranged in the same way as in the ordinary Siemens armatures. Fig. 8 shows how the respective coils are wound. I have here shown seven segments to each commutator C D, numbered from 1 to 7. Commencing at segment 1 of commutator C, the coarse wire w passes around the drum as many times as is desired and terminates at segment 2. The fine wire v from segment 1 of commutator D passes around the drum alongside 110 or outside of the coarse wire, but is wound with more turns, and terminates at segment 2. I have shown the coarse wires as having only one turn, and the fine wires as having two turns, around the drum. The yoke F, with its coils 115 G G, is mounted on the shaft E, as before, and its pole-pieces $m m$ extend down and come close against the periphery of the drum. This yoke constitutes, as before, the motor for driving the shaft, and the brushes (not shown) are 120 carried by the shaft, as before described.

I have shown in Fig. 9 a wheel, E', which may serve as a brake-wheel. In Fig. 10 is shown a modification of the brake and regulating mechanism, wherein a brake-shoe, O', 130 is applied to the rim of such a wheel, E'. A lever, P, having interchangeable fulcras $f' f^2$ is connected at its end to the core Q of a solenoid, or rather of two opposing solenoids, S'

and T'. The former is wound with direct and shunt coils in the low-tension circuit, and the latter with direct and shunt coils in the high-tension circuit. Thus the coils and switches 5 are seen to be differently arranged from the construction first described. When any of the coils of the magnet S' are being used as the chief regulating-coils, the fulcrum will be at f'. When coils of magnet T' are so used, the 10 fulcrum will be at f'.

The constructions and arrangements of parts shown in Figs. 8, 9, and 10 are shown simply as examples of the modifications of which my invention is susceptible.

15 It is not essential to my invention that the regulation of the machine be effected through the medium of a friction-brake, as other means of controlling the machine may be applied, as the judgment of the mechanician or electrician 20 may dictate. One feasible method is to vary the position of the commutator-brushes relatively to the yoke F. It being remembered that the positions of the poles in the ring B are determined by the positions of the brushes 25 which deliver the primary current, and that the rotation of the brushes is due to the "lead" of these poles in advance of the poles of the yoke F, it is obvious that the rotative tendency of the yoke may be varied by increasing 30 or diminishing this lead, and that in this way the speed of rotation may be controlled. If the magnets T and S be connected in some way to the brushes, so that as one or the other is more or less excited the brushes will be advanced or retrograded until an equilibrium is 35 reached, a practical method is attained of regulating the machine.

Figs. 11 and 12 show a construction of translator which is regulated on this principle. 40 The Gramme ring revolves, carrying the commutator-segments, while the yoke F and the brushes are stationary. The magnets S and T are connected, as before, to opposite ends of a lever, P, which in this construction is fulcrumed 45 in the middle. This lever carries brackets V V, in which are mounted traction-wheels W W, either of which, if lowered by the descent of its side of the lever, may touch an annular rail, X, carried by the Gramme ring. Each wheel 50 W has a pinion, w', which gears with a toothed wheel, y. The two wheels y y are fixed on opposite ends of a shaft, Y, which is hung in fixed bearings, and carries a worm, Y'. This worm 55 meshes with a worm-wheel, Z, which is fixed on a sleeve, z, on which sleeve are mounted the commutator-brushes c c and d d. When one magnet, S or T, draws down its end of the lever P, the corresponding wheel, W, is moved against the track X and is rotated thereby, 60 consequently rotating shaft Y and its worm, and consequently turning the worm-wheel and the brushes either forward or back. When it is desired to regulate by the opposite magnet—by S, for example, if T has been used— 65 the tendency would be to turn the brushes in the wrong direction. To correct this, I provide two worms, Y', one having a right-hand

and the other a left-hand thread, and both arranged to slide like a sleeve on the shaft Y, and to be fastened thereon by a set-screw. In 70 shifting from one magnet to the other I slide this sleeve until the other worm is in mesh with the wheel Z. The wheel turns at the same time. The brushes and sleeve z may turn with the wheel and be afterward set to 75 place, or a set-screw, z', may be loosened and the brushes held stationary while the wheel Z turns, after which it is tightened again.

It is obvious that with my translator it is immaterial whether the coils are stationary 80 and the yoke and brushes revolve, or the coils revolve while the yoke and brushes are stationary.

By the term "commutator" as used herein I mean both the commutator segments and the 85 brushes. Either of these members may be stationary and the other rotative. By a "rotary commutator" I mean a commutator one member of which is rotative, as distinguished from a vibratory commutator. 90

While my invention is designed chiefly for translators wherein the induced currents are collected and rectified by a commutator, so that a single continuous induced current is delivered from the machine, yet it is apparent that 95 it is in part applicable to those translators or transformers wherein there is no secondary commutator, and which consequently deliver alternating currents to as many distinct secondary circuits as there are distinct secondary 100 induction-coils. Whenever such a machine is desirable, my means of adjustment and control may be applicable, provided only that the electric motive devices in the secondary circuit by which the control is effected are of 105 such character as to be suited to the alternating currents in that circuit.

I am aware that translators of the character just described have been proposed in which, when the rotation of the parts exceeds a certain speed, a centrifugal cut out shunts the primary circuit around the machine, thereby cutting off the current therefrom until the speed is reduced. Such a construction would be highly objectionable, inasmuch as the inductive action would cease whenever the speed became excessive, so that the lights fed by the secondary circuits would be extinguished. In my machine the regulation is accomplished without interruption of the primary current, it being effected by controlling the rapidity of alternation of the current in the primary coils. 115

I claim as new, and desire to secure by Letters Patent, the features and combinations defined as follows, substantially as hereinabove set forth, namely:

1. An electric inductive translator having a series of induction-coils and a commutator for alternating the current in said coils, combined with an automatic regulating device controlling the commutator, and thereby governing the rapidity of alternation of current in the coils. 125 130

2. An electric inductive translator having a series of induction-coils and a rotary commutator for alternating the current in said coils successively, combined with an electrically-controlled regulating device acting upon the commutator, and thereby governing the speed thereof and the rapidity of alternation of current in the said coils.
3. An electric inductive translator having a rotary commutator, combined with an electro-magnetically-operated speed-regulating device for controlling the speed of rotation of the commutator.
4. An electric inductive translator having a rotary commutator, combined with a speed-regulating device for controlling the speed of rotation of the commutator, and an electro-magnet installed in the secondary circuit, connected to and actuating said speed-regulating device.
5. An electric inductive translator having a rotary commutator, combined with a speed-regulating device for controlling the speed of rotation of the commutator, and an electro-magnet installed in the primary circuit, connected to and adapted to influence said speed-regulating device.
6. An electric inductive translator having a rotary commutator, combined with a speed-regulating device for controlling the rotation of the commutator, an electro-magnet installed in the primary circuit, and an electro-magnet installed in the secondary circuit, both of said magnets being connected to and adapted to influence said speed-regulating device.
7. An electric inductive translator having a rotary commutator, combined with a speed-regulating device for controlling the rotation of the commutator, electro-magnets for actuating said device, and switches for controlling the excitation of said magnets.
8. An electric inductive translator having a rotary commutator, combined with a speed-regulating device for controlling the rotation of the commutator, an electro-magnet for actuating said device installed in one circuit, another electro-magnet installed in the other circuit and tending to resist said actuating-magnet, and means, such as described, for varying the strength of said magnets.
9. An electric inductive translator having a rotary commutator, combined with a speed-regulating device for controlling the rotation of the commutator, oppositely-acting electro-magnets for actuating said device, and adjustable retractile springs acting upon said device.
10. An electric inductive translator having a rotary commutator, combined with a speed-regulating device for controlling the rotation of the commutator, a lever connected at its middle portion to said device, oppositely-acting electro-magnets for actuating said device connected to said lever, and the fulcrum of said lever adjustable to either side of its point of connection with said regulating device,
- whereby the action of the respective magnets may be reversed.
11. An electric inductive translator having a rotary commutator, combined with a speed-regulating device for controlling the rotation of the commutator, an electro-magnet for actuating said device, installed in a shunt of the secondary circuit, and means, such as described, for varying the strength of said magnets.
12. An electric inductive translator having a rotary commutator, combined with a speed-regulating device for controlling the rotation of the commutator, an electro-magnet for actuating said device, installed in a shunt of the secondary circuit, another electro-magnet installed serially in the primary circuit and adapted to act on said regulating device in opposition to said shunt-magnet, and means, such as described, for varying the strength of said magnets.
13. An electric inductive translator having a rotary commutator, combined with a speed-regulating device for controlling the rotation of the commutator, an electro-magnet or magnets for actuating said device, having two or more coils installed in shunts of the primary and secondary circuits, respectively, and a switch for cutting out one or more of said coils.
14. An electric inductive translator having a rotary commutator, combined with a speed-regulating device for controlling the rotation of the commutator, an electro-magnet or magnets for influencing said device, having two or more coils installed serially in the primary and secondary circuits, respectively, and a switch for cutting out one or more of said coils.
15. An electric inductive translator having a rotary commutator, combined with a speed-regulating device for controlling the rotation of the commutator, electro-magnets for actuating said device, with their coils installed in shunts and serially in the primary and secondary circuits, respectively, and switches for cutting out any of said coils, whereby the apparatus is adaptable to different conditions of use.
16. An electric inductive translator having a rotary commutator, combined with a friction-brake for controlling the rotation of the commutator, and electro-magnetic devices for applying said brake.
17. An electric inductive translator having a rotary commutator, combined with a friction-brake for retarding the rotation of the commutator, an electro-magnet tending when excited to apply said brake, another electro-magnet tending when excited to release said brake, and means, such as described, for varying the relative pull of said magnets.
18. An electric inductive translator having a rotary commutator with its rotating member mounted on a shaft, combined with a friction-brake constructed to act longitudinally of said

- shaft, and regulating electro-magnets adapted to press said brake against said shaft with varying tension.
19. An electric inductive translator having a rotary commutator, combined with a vertical shaft carrying the rotating member thereof, a stepped bearing for lower end of said shaft, an oil-cup borne by the upper part of said shaft, a friction-brake engaging said shaft to within said cup, whereby it may be submerged in oil, and regulating electro-magnets adapted to press said brake downward with varying tension.
20. An electric inductive translator, combined with an electromotor driving the rotative member of its commutator, and an electrically-controlled speed-regulator acting upon the commutator and governing the speed of its rotation.
21. An electric inductive translator, combined with an electromotor driving the rotating member of its commutator, and an electro-magnetically-operated speed-regulator for controlling the rotation thereof.
22. An electric inductive translator having a series of induction-coils, a rotary commutator for alternating the current in said coils successively, an electromotor for driving the brushes of said commutator, and an adjustable connection between the moving member of said motor and said brushes, whereby the one may be advanced or retrograded relatively to the other.
23. An electric inductive translator having a series of induction-coils, a rotary commutator for alternating the current in said coils successively, a shaft carrying the brushes of said commutator, a magnetic bridge on said shaft arranged with its polar terminals in inductive proximity to the induction-coils, thereby constituting an electromotor for driving said shaft and brushes, and an adjustable connection between said brushes and said bridge, whereby the lead of the brushes may be varied.
24. An electric inductive translator having a circular core wound with the induction-coils, a rotary commutator, and a shaft carrying the brushes of said commutator, combined with a magnetic bridge mounted on said shaft, arranged with its polar terminals in inductive proximity to the poles of said core, and an adjustable connection between the brushes and said bridge, whereby the brushes may be advanced or retrograded, thereby varying the positions of the poles in the core relatively to said bridge.
25. The combination, with an electric inductive translator, its rotary commutator, and a speed-regulating device for said commutator, of an electro-magnet for operating said device, constructed with two or more cores connected together and acting on one armature, and their coils installed in different circuits or branch circuits, and a switch adapted to control the currents passing through said coils.
26. The combination, with an electric inductive translator, its rotary commutator, and a speed-regulating device for said commutator, of an electro-magnet for operating said device, and the armature of said magnet adjustable toward or from the poles thereof to vary the pull of said magnet.
27. An electro-magnet consisting of two or more cores connected together through one base-plate, a single armature receiving the attraction of said cores, and the several coils connected in different circuits or branch circuits, in combination with a switch adapted to cut out one or more of said coils.
28. An electro-magnet consisting of two or more cores connected together through one base-plate, a single armature receiving the attraction of said cores, and a magnetic connection between said armature and base-plate, consisting of a core projecting from the one part and moving freely in a socket in the other.
- In witness whereof I have hereunto signed my name in the presence of two subscribing witnesses.
